P. M. KUEHN

2,066,292

GASHOLDER

Filed Sept. 9, 1932

UNITED STATES PATENT OFFICE

2,066,292

GASHOLDER

Paul M. Kuehn, Baltimore, Md., assignor, by
mesne assignments, to Kopper's Company, a
corporation of Delaware

Application September 9, 1932, Serial No. 632,447

1 Claim. (Cl. 48—176)

This invention pertains to waterless gas holders and relates more particularly to the sealing means interposed between the usual piston-like closure and the inner face of the shell or body of the holder.

The invention has to do with a structure where-
in a fluid sealing medium is employed in con-
junction with mechanical elements interposed
between the piston and the inner wall of the
holder. Holders of this type are shown in Let-
ters Patent to Jagschitz No. 1,275,696, dated
August 13th, 1918 and the patent to Kuehn No.
1,711,392, dated April 30th, 1929. These two
patents are typical of the commercial structures
used in this country and abroad.

In my copending application filed September
9, 1932, Serial No. 632,446, there is set forth and
claimed a structure embodying a series of rub-
bing bars or shoes arranged in vertical relation;
a gutter for a sealing medium, which medium co-
operates with the shoes to effect a seal between
the piston closure and the shell; and means for
urging the shoes into facewise contact with the
inner face of the wall of the shell.

The present invention is directed to the same
general end but has for its object the provision
of a special equalizing mounting for sustaining
the bars in place, which mounting also provides
the means whereby pressure may be applied to
the bars to move them outwardly into sealing
relation with the shell of the holder.

The invention is illustrated in the annexed
drawing, wherein:

Fig. 1 is a vertical sectional view of so much
of the piston closure, shell and related parts as is
necessary to an understanding of the invention;
and

Fig. 2 a perspective view of the same as seen
looking toward the inner face of the shell.

In the drawing, 1 denotes the shell and 2 the
piston-like closure located therein which is sur-
rounded by a gutter for the reception of the
sealing medium.

The gutter is defined by the vertical wall 3
of the piston; bottom plate 4; clamping means,
denoted generally by 5, for the lower portion of
the flexible gutter element 6, generally produced
from canvas; and the shoes, to the lowermost
of which (denoted by 7) the uppermost portion
of the flexible element 6 is secured. Spreader or
spacer elements 8 are usually present to hold
the canvas element 6 out of rubbing contact with
the inner face of the shell as the piston moves
up and down.

The upper portion of the canvas is folded over

the upper flattened section of the spreader 8 and
the parts are secured tightly against the inner
face of rubbing bar 7 by an overlying plate 9
and bolts 10 which extend through the various
elements including the bar or shoe 7.

The construction thus far described is old.

Located above the bar 7 is a second bar 11.
These bars are in vertical alignment and slightly
spaced apart.

Extending inward from the bar 7 are spaced 10
brackets or plates 12 and 13, said elements be-
ing shown as provided with lugs extending
through the bar and welded thereto. Other
means for securement may of course be employed.

A pair of plates 14 and 15 are mounted in the 15
same manner on bar 11 and stand, respectively,
in vertical alignment with the plates or brackets
12 and 13.

Extending through plates 12 and 13 is a cross
pin 16 and a similar pin 17 is carried by the 20
upper plates. These pins form the bearings and
supports for a pair of links 18 and 19 which are
held in proper spaced relation by spacer sleeves
20 and 21.

A shaft 22 is located between the links, its re-
duced ends finding bearings therein. Extending
upwardly from the shaft is a weighted lever
23 fulcrumed at 24 to a bracket 25 secured to the
piston structure. The lever, acting through the
links 18 and 19 and the pins 16 and 17, forms 30
the supporting means for the shoes as well as the
pressure applying means therefor.

The construction above described forms in ef-
fect an equalizing mechanism between the two
shoes. If one is forced inwardly by an obstruc- 35
tion the other will be subject to greater pressure
and hence the seal will be maintained between
such shoe and the shell by reason of the fluid
sealing medium which is present between such
members or parts.

While the adjacent edges of the bars are spaced
apart so that the sealing medium may pass out-
wardly at such point, as well as over the upper
edge of the upper shoe, still a strip of canvas, as
26 (Fig. 2) may be secured to the inner face of
each shoe covering or closing off the passage or
space between the adjacent edges. The strip will
be bowed or of such width as not to affect the in-
dependent movements of the shoes.

The normal level of the fluid in the gutter is
above the upper edge of the upper shoe but when
the strip 26 is not present the lower shoe will
continue to function so long as the fluid level is
above the upper edge thereof.

Reference has heretofore been made to a liquid sealing medium. For this purpose tar, oils, or any material which will form a tight seal between the rubbing bar and the inner face of the shell 5 may be employed.

What is claimed is:

In a waterless gas holder, the combination of 10 a shell; a piston-like closure therein; a pair of vertically disposed separated rubbing bars in contact with the inner face of the shell; a pair of fixed spaced brackets extending inwardly from the inner face of each bar; a horizontally dis-

posed pin mounted in and extending between each pair of brackets; connecting links, one for each pair of brackets, mounted for swinging movement on said pins; a shaft connected to the links intermediate their ends; and means associated with said shaft acting at all times to move the shaft toward the shell and as a consequence to apply pressure through the links and brackets to the rubbing bars, whereby the bars may be forced independently toward the shell with a full 10 and fair bearing thereon.
